UNITED STATES PATENT OFFICE.

RICHARD W. BURNETT, OF CHICAGO, ILLINOIS.

CAR-ROOF.

1,265,739.

Specification of Letters Patent. Patented May 14, 1918.

Application filed June 29, 1917. Serial No. 177,690.

To all whom it may concern:

Be it known that I, RICHARD W. BURNETT, a citizen of the United States of America, residing at Chicago, in the county of Cook 5 and State of Illinois, have invented certain new and useful Improvements in Car-Roofs, of which the following is a specification, reference being had therein to the accompanying drawings.

10 The invention relates to car-roofs of the type in which the roofing-sheets are arranged below the carlines and are provided with upstanding flanges housed and weather-proofed by said carlines, the subject matter 15 being related to that of my co-pending application, Serial Number 177,689. The invention comprises the novel means of supporting the sheets as hereinafter set forth.

In the drawings:

20 Figure 1 is a cross-section through a carline, showing portions of adjacent roofing sheets and the means for supporting the same;

25 Fig. 2 is an end elevation of the supporting clip detached;

Fig. 3 is a plan view; and

Fig. 4 is a side elevation thereof.

A is a carline of inverted channel form provided with laterally and outwardly extending flanges B at the base thereof. C are the roofing sheets arranged beneath the carline, having upstanding flanges D extending within the channel and terminating at their upper ends in laterally, outwardly extending 30 and preferably slightly return bent portions E. To form a simple means of supporting the sheets I provide clips, preferably of the construction shown in Figs. 2 and 4, comprising a portion F for fitting 35 against the under face of the top of the carline and depending portions G at opposite ends terminating in laterally, inwardly extending portions H. There is also provided a portion I which extends centrally 40 against the under face of the top of the carline and depending portions G at opposite ends terminating in laterally, inwardly extending portions H. There is also provided a portion I which extends centrally 45 from one end of the clip. The clips thus formed are secured to the carlines, preferably by spot-welding the portion F to the upper portion of the carline or securing it by any other suitable means.

50 In assembling, the sheets are arranged beneath the carlines and the flanges D thereof are pressed upward, passing between the inwardly-extending portions H of the clip, and are then moved outward to engage the 55 portions E with the portions H. The portion I is then bent downward to extend

between the flanges D and to operate as a spacer which holds the laterally-extending portions E and H in engagement with each other. This will preclude the accidental 60 disengagement of the sheets, but whenever it is desired to remove a sheet, by bending back the spacer portions I this may be readily accomplished.

What I claim as my invention is:—

1. In a car-roof, the combination with an inverted channel carline, of roofing sheets having upstanding flanges housed within the channel of the carline, said flanges terminating in laterally, outwardly extending 70 portions, and a supporting clip secured within the carline having depending end portions terminating in laterally, inwardly extending portions for engaging and supporting the laterally, outwardly extending 75 portions of the sheets, said clips being also provided with a portion bendable to extend between the flanges of said sheets and form a spacer to retain the same in engagement with the clips.

2. In a car-roof, the combination with an inverted channel carline, of roofing sheets having upstanding flanges housed within the channel of the carline, said flanges terminating in laterally, outwardly extending 85 portions, and a supporting clip having a portion fitting against and attached to the top portion of the carline, depending portions adjacent to the opposite sides of the carline terminating in laterally, inwardly 90 extending portions and a portion extending from the attachment portion of the clip centrally of the carline, the inwardly-extending portions of said clip forming supports with which the laterally-extending 95 portions of the sheet flanges may be engaged, and the central portion of the clip being bendable downward to form a spacer between said flanges, retaining the same in engagement with their supports.

3. In a car roof, the combination with a carline of inverted channel section, of roofing sheets having upstanding flanges housed within the channel of the carline, said flanges terminating in laterally, outwardly 105 extending portions, and a clip for supporting said flanges comprising a portion fitting against the upper part of the carline and spot-welded thereto, depending portions adjacent to the opposite sides of the carline 110 terminating in laterally, inwardly extending portions forming supports with which

- 2
- the outwardly-extending portions of the sheet flanges may be engaged, and a portion projecting from said clip centrally of the carline bendable downward to extend between said flanges and to retain the same in engagement with each other.
5. In a car-roof, the combination with an inverted channel carline, of roofing sheets having upstanding flanges housed within said carline, and means permanently attached to said carline within the channel thereof for engaging said flanges to support the sheets.
4. In a car-roof, the combination with an inverted channel carline, of roofing sheets having upstanding flanges housed within 10 said carline, and means permanently attached to said carline within the channel thereof for engaging said flanges to support said sheets.

Copies of this patent may be obtained for five cents each, by addressing the "Commissioner of Patents, Washington, D. C."

5. In a car-roof, the combination with a carline of inverted channel section, of roofing sheets having upstanding flanges housed within said carline, means permanently attached to the carline within the channel thereof adapted for the detachable engagement of said flanges therewith to support 15 said sheets, and means also permanently attached to the carline for locking said flanges from disengagement.

In testimony whereof I affix my signature.

RICHARD W. BURNETT.
